UNITED STATES PATENT OFFICE.

FRANK H. LOMBARD, OF DONGOLA, ILLINOIS, ASSIGNOR OF ONE-HALF TO S. O. BOYD, OF DONGOLA, ILLINOIS.

FIRE-ESCAPE.

No. 926,342.

Specification of Letters Patent.

Patented June 29, 1909.

Application filed June 26, 1908. Serial No. 440,530.

To all whom it may concern:

Be it known that I, FRANK H. LOMBARD, a citizen of the United States, residing at Dongola, in the county of Union, State of Illinois, have invented certain new and useful Improvements in Fire-Escapes; and I do hereby declare the following to be a full, clear, and exact description of the invention, such as will enable others skilled in the art 10 to which it appertains to make and use the same.

This invention relates to fire escapes and more particularly to that class which are suspended from the wall of the building in 15 connection with which they are used and it is the object of my invention, primarily, to provide an escape of this class which when not in use, may be suspended to one side of the window from which it is to lead in case 20 of fire and with its lower end above the level of the ground and which may be readily moved to position beneath the window and supported at its lower end in proper position to permit of descent of the residents of 25 the building.

The escape embodied in my invention is in the form of a chute down which the residents of the building may slide in case of fire and I preferably form the chute with 30 sides and a bottom the upper edges of the sides being over turned to afford hand rails or grips by grasping which the person using the escape may regulate the speed of their descent.

35 In the accompanying drawings, Figure 1 is a view in elevation of a building showing my fire escape applied thereto, the escape being shown in normal position in full lines and in operative position in dotted lines, 40 Fig. 2 is a side elevation of the escape showing its operative position in full lines and normal position in dotted lines, Fig. 3 is a transverse sectional view through the escape, Fig. 4 is a view similar to Fig. 1 but showing a slight modification of the invention, 45 and, Fig. 5 is a bottom plan view of a portion of the chute embodied in the two forms of the invention. Figs. 6 and 7 are, respectively, a front and a side elevation of a further 50 modification of the invention.

In the drawings, there is shown the wall of a building indicated by the reference character A and a window which opens through the said wall and is indicated by the refer-

ence character B the sill of the window 55 frame being indicated by the character C.

Supported from the wall A in spaced relation with respect thereto by means of suitable brackets 10, which may or may not be integral, is a track, one portion of which, 60 indicated by the numeral 11, extends directly beneath the window sill C and substantially the length thereof, the track being extended upwardly at an angle, as at 12, from this portion 11 and thence horizontally as at 65 13, the portion 13 of the track being of course located in a plane above that occupied by the portion 11 of the said track.

The escape proper embodied in my invention is preferably formed of a single length 70 of sheet material such as copper which is worked or stamped to form a bottom or slide 14 and sides 15 which, in conjunction with the bottom, form or constitute a chute, the upper edges of the said sides being over 75 turned as indicated by the numeral 16, and clearly shown in Fig. 3 of the drawings, so as to afford a hand hold at each side of the chute which may be grasped by the person using the escape whereby they may regulate 80 the speed of their descent. At its upper edge, the bottom 14 of the chute is formed with two integral hooks 17 which are engaged with the track heretofore mentioned, the chute being suspended normally from 85 the portion 13 of the track and being slideable down the inclined portion 12 thereof and into position to be suspended from the portion 11. When the chute is suspended from the portion 13 of the track, it is raised 90 a distance equal to that between the planes of the portions 11 and 13, but when the chute is slid upon the track so as to hang from the portion 11, it is lowered the same distance, and in order to support the chute in inclined 95 position I provide adjacent the lower end of the chute a foldable support.

The support mentioned above is in the form of a pair of legs or standards 19 which are pivoted at their upper ends to ears 20 100 secured upon the under side of the chute adjacent the lower end thereof and are connected adjacent their lower ends by means of a cross piece 21. When the chute is slid to the position last stated, the support is lowered to the position shown in full lines in Fig. 2 of the drawings, so as to support the lower end of the chute above the surface of 105

the ground and away from the wall of the building, thereby permitting the occupants of the building to slide down the chute, it being understood, as clearly shown in Fig. 1, 5 that when the chute is in this position, it is directly beneath the window. When the chute is in normal position or, in other words, not in use, the support is folded up, as clearly shown in dotted lines in Fig. 2 10 of the drawings. In order to brace the chute, it being formed of sheet copper or other sheet metal, transversely-disposed straps 22 are riveted or otherwise secured to the under face of the bottom portion 15, said straps 15 extending at their ends across the outer surfaces of the sides.

In the form of my invention shown in Fig. 4 of the drawings, the inclined track illustrated in the other figures is dispensed 20 with and an ordinary straight track 23 is employed, there being, however, an extra pair of hooks 24 provided upon the under side of the chute so that the chute may be supported above the ground. In this form 25 of the invention, the chute is identical with the one previously described except for the provision of the extra pair of hooks 24.

In the further modification shown in Figs. 6 and 7, the straight track 23 is disposed at 30 right angles to the wall A, and has one end embedded therein and supported in any preferred manner. This form of the invention is designed for use primarily where one side of the building fronts on an alley, the chute 35 being supported at all times in operative

position by its hooks 17 and its standards or legs 19. In this form of the invention, the escape is always ready for use.

What is claimed is:

1. A fire escape of the class described comprising a chute arranged to be suspended from the wall of a building, and a foldable support for the lower end of the chute. 40

2. A fire escape, comprising a track provided with wall-attaching devices, a chute suspended at its upper end from the track and movable along the same, and a foldable support carried by said chute at its lower end. 45

3. The combination with the wall of a building and a window therein, of a track 50 secured to the wall in spaced relation thereto, said track extending directly beneath the sill of the window, thence upwardly at an angle to a plane above that of the sill, and finally horizontally, and a chute suspended at its 55 upper end normally from the last mentioned portion of the track, and movable along said track into position to hang from that portion thereof beneath the window, said chute being arranged to hang directly from 60 the track parallel with the wall when in its normal position, and to be swung outwardly from the wall when disposed below the window.

In testimony whereof, I affix my signature, in presence of two witnesses.

FRANK H. LOMBARD.
